(57) **CLAIM**

The ornamental design of audio input/output device, as shown and described.

DESCRIPTION

FIG. 1 is a perspective view of an audio input/output device in accordance with the present invention;

FIG. 2 is a front view thereof;

FIG. 3 is a right view thereof;

FIG. 4 is a rear view thereof;

FIG. 5 is a left view thereof;

FIG. 6 is a top view thereof, and,

FIG. 7 is a bottom view thereof.

The features shown in broken lines in the various Figures are for illustrating environmental structure and form no part of the claimed design.
